STRAIN CARRIER FOR TWIN STRINGS OF
INSULATORSDavid Charles Hubbard, Centralia, Mo., assignor
to A. B. Chance Company, Centralia, Mo., a
corporation of Missouri

Application January 5, 1950, Serial No. 136,995

17 Claims. (Cl. 254—67)

1

The present invention relates to strain carriers for twin strings of insulators, and is particularly concerned with the provision of an improved tool adapted to relieve the strain from one of the strings of dead end insulators where two strings are mounted in parallel and attached to line yoke place.

One of the objects of the invention is the provision of an improved tool which provides a maximum insulation because the metallic tightening mechanism is located outside or beyond the torque arms or lever arms, leaving the full length of the wooden insulating members between the lever arms available as insulation.

Another object of the invention is the provision of an improved tool construction which includes parallel tension boards so that the same existing torque arms, which are designed for yoke plates, and that are now employed on working de-energized lines may be used with the present tools.

Another object is to provide an improved strain carrier which is adjustable in length for the variance in number of insulating units or variance in the dimensions of the hardware employed, and in which the adjustments are readily made by merely removing one eye nut.

Another object of the invention is the provision of an improved tool in which the wooden tension members are reinforced at the hinge joint and prevented from spreading, even though the wooden member splits or becomes checked, and in which the operating jack is positioned close to the operator.

Another object of the invention is the provision of an improved strain carrier which is applicable to different types of yoke plates by employing an adapter.

A further object of the invention is the provision of an improved strain carrier in which the force applying element is so arranged that it exerts a push on the tilting lever instead of a pull, thereby eliminating metallic parts on the wood and insulators between the two lever arms and increasing the insulation over the devices which exert a pull on the levers by having metallic parts between the two tilting levers.

Referring to the drawings, of which there are two sheets,

Fig. 1 is a top plan view of the present strain carrier applied to a twin insulator installation and in position to relieve the strain on the right hand string of insulators;

Fig. 2 is a fragmentary elevational view, taken from the right of Fig. 1;

Fig. 3 is a fragmentary plan view like Fig. 1,

2

showing the use of the same tilting lever on a different type of yoke, without the adapter;

Fig. 4 is a fragmentary sectional view, taken on the plane of the line 4—4 of Fig. 1, looking in the direction of the arrows and on a larger scale;

Fig. 5 is a similar fragmentary sectional view, taken on the plane of the line 5—5 of Fig. 1, looking in the direction of the arrows;

Fig. 6 is a fragmentary sectional view, taken on the plane of the line 6—6 of Fig. 1, looking in the direction of the arrows;

Fig. 7 is a view in perspective of the adapter by means of which the same tilting lever which is used on solid flat yokes in Fig. 3 may be applied to the different type of yoke, as shown in Fig. 1.

Referring to Figs. 1 and 2, the present strain carrier is intended to be used for relieving the strain on one of a pair of strings of insulators, such as the two strings indicated at 10 and 11 (Fig. 1), each of which is comprised of a plurality of similar insulators 12.

The ends of these strings are pivotally mounted on the two yokes 13 and 14 by means of the bolts or rivets 15 pivotally mounted in the lugs 16. The yokes in question are usually provided with a pair of centrally located pivot flanges 17 and 18 at the apex of the triangular yoke, these flanges being provided with a through bolt 19 for securement of the chain link 20.

Two types of yokes are employed, such as that shown at 13 in Fig. 1, in which the yoke has a pair of triangular openings 21, 22 and the yoke 23 of Fig. 3, which comprises a flat triangular plate with rounded corners.

The present tilting levers are applicable to both types of yokes; and since the yoke 23 is simplest, it will be described first. Yoke 23 has apertures at its two lower corners (Fig. 3) for receiving the stub bolts 24, 25, which pass through the parallel flanges of the insulator supporting fixture 26, and are secured by cotter pins.

The tilting levers in Fig. 1 are indicated in their entireties by the numbers 28 and 29, and they are identical in construction. For example, in Fig. 3 the tilting lever 28 is applied to the yoke 23. The tilting lever 28 comprises an elongated metal casting which tapers in width toward its actuating end 30. At that end it is provided with a tubular formation 31, serving as a bearing by means of its through bore 32.

The tilting lever 28 may have its tapered portion formed by a central web 33 bounded by the two reinforcing border flanges 34 and 35. This construction makes the lever lighter in weight and stronger. At its left end in Fig. 3 the tilting

lever 28 has a laterally turned end portion 36 which may be substantially triangular, ending in an apex 37.

The laterally turned end portion 36 comprises a pair of flanges 38 and 39 (Fig. 5) separated by a rectangular slot 40. The slot 40 is wide enough to receive the flat plate 23; and the tilting lever 28 or 29 is suitably thickened, as indicated by the offsets 41 at the end, so that there may be sufficient body left when the slot 40 is enlarged to receive the yoke 13.

The base 42 of the slot 40 (Fig. 5) extends along a diagonal line, as again indicated at 42 in Fig. 3, so that it may fit against the diagonal edge 43 of the yoke 23. The lever 28 is adapted to bear down against the edge 43 of the yoke 23 by means of the base 42 of the slot.

At the triangular point 37 of the laterally turned end 36 of the lever 28 there is formed a kind of tubular enlargement 44 which has a through bore 45 for receiving the cylindrical body 46 of an eye bolt 47. This eye bolt bears against the lower (Fig. 3) straight edge 48 of the yoke 23.

The right and left hand portions of the yoke 23 taper toward the bolt 25; and the tilting lever 28 would slip off the tapered part of the yoke 23 were it not for the fact that the insulator fixture 26 has rounded attaching flanges 49. The tilting lever 28 has its border flange 35 curved at 50 on each of the legs 38 and 39 to bear against the round attaching flanges 49 of the insulator string fixtures 26.

Thus the fixtures 26 keep the tilting levers 28 from passing off the tapered ends of the yokes 23. The slot 40 is of uniform width between the flanges 38 and 39 from the base 42 to a pair of diagonal shoulders 51 and 52 (Fig. 5) beyond which the laterally turned portion 36 of the lever has a wider slot, indicated by the number 53. This wider slot 53 is wide enough to pass the border flanges of the thicker yoke 13 of the type shown in Fig. 1.

Referring to Fig. 1, the yoke in this case has a thin web 54 surrounding each of the triangular apertures 21 and 22; and the web 54 is surrounded by the substantially triangular border flange 55. The border flange 55 extends diagonally downward in Fig. 1 on the top of the yoke 13, and is adapted to fit against the two shoulders 51 and 52 (Fig. 5 of the lever 28 in Fig. 1).

The laterally turned end portion 36 of this lever then extends down across the triangular aperture 22; and the cylindrical body of the eye bolt 47 passes through the triangular aperture 22 and fits in the rounded corner of aperture 22 in Fig. 1.

The two flanges 38 and 39 of the tilting levers 28 or 29 are provided with laterally projecting bosses 56 (Fig. 3) with through bores 57. This through bore 57 is adapted to receive a screw bolt 58 (Fig. 1) which is provided with a suitable head and nut, and the screw bolt 58 supports an adapter of the type shown at 59 in Fig. 7.

This adapter 59 may consist of a relatively small diamond shaped metal member, which may be in the form of a flat plate, or which may be cast with a border flange 60 and web 61. In either event, the adapter 59 fits in the slot 40; and its upper flat surface 62 fits against the base 42 of the slot 40. The opposed flat surface 63 of the adapter bears against the diagonal edge 64 of the yoke 13 when the adapter is used. The adapter is held in place by the through bolt 58, which passes through an aperture 65 at the upper left corner of the adapter 59 in Fig. 7.

The tilting levers 28 or 29 have their border

flanges provided with enlargements 66 with a through aperture 67 at a point which is within the boundaries of the insulators 12 so that aperture 67 may support an eye bolt 68 having an eye 69 large enough to receive a wooden rod 70 serving as part of an insulator cradle.

Another similar enlargement 71 is formed on the outer surface or edge of the rounded laterally extending portion 36 provided with an aperture 72 for receiving another similar eye bolt 73. The eye bolt 73 carries the second rod, which forms an insulator cradle; and the two parallel rods 70 are supported by eye bolts from the two tilting levers 28, 29.

Thus the mechanism supports the insulator after its strain has been relieved; and while the ends of the insulator string are being attached or detached from the yoke.

At its free end each tilting lever 28 and 29 is engaged by the wooden tension arms 74, 75 by means of suitable pivot assemblies 76, 77. The tension arms may be of suitable length to cover the complete range of insulator string lengths; and various tension arms may be used interchangeably with the tilting levers or torque arms 28, 29.

Each tension arm consists of an elongated flat strip of well dried tough wood coated with a suitable layer of insulating varnish; and the strips 30 are preferably rectangular in cross section, flat, and relatively wide as compared to their thickness.

At the jack end of the tension arms, that is, the upper end in Figs. 1 and 2, the two tension 35 arms are joined and held in spaced relation, parallel to each other, by a metal block 78 (Fig. 6), which has flat ends 79 and 80 for engaging the tension arms 74 and 75. Registering through bores 81 and 82 are provided through the block 40 78 and through the tension members 74 and 75 for receiving the screw bolts 83, which are provided with nuts and tightened to clamp the tension members 74, 75 against the block 78.

The block 78 is provided with a central threaded bore 84, the threads of which are complementary to a screw shaft 85; and the block is preferably provided with a tubular extension 86 about the bore 84 to increase the area of engagement between the threads of the block 78 and the threads of the shaft 85.

The block 78 may also be provided with tubular extensions 87 about each of the bores 81, 82, extending into apertures in the tension members 74, 75 for increasing the area of contact between the block and the tension members; and the bolts 83 are provided with suitable washers. The length of the tubular extensions 87 is substantially equal to the thickness of the tension members 74, 75.

At its outer end the shaft 85 may be squared or provided with a hexagonal portion 88 to be received in the complementary socket of a ratchet lever 89.

At its inner end the shaft 85 is rotatably engaged in a socket in the sliding block 90, which is provided with guide flanges 91 (Fig. 4) for engaging the inside of the wooden tension members 74, 75, and with additional guide flanges 92 for engaging the edges of the wooden tension members 74, 75. Thus the block 90 is adapted to slide between the tension members 74 and 75.

At its inner end the block 90 is provided with a partially circular socket 93 (Fig. 1) for engaging the cylindrical end or bearing portion 30 of the upper tilting lever 28.

The guide flanges 91, 92 project below the body of the block 90 (Fig. 2), providing a recess large enough to receive the bearing portion 31 of the tilting lever 28; and the tilting lever is provided with a stub shaft 94, passing through the aperture 32 and engaging shallow grooves 93, which are formed in the lower edge of the downwardly projecting portion of the block 90.

The stub shaft 94 is confined by being mounted between the tension members 74 and 75; and the block 90 may be secured on the end of the shaft 85 by providing an annular groove in the shaft, indicated at 56, and by the transverse pin 97 passing through the block and located in the annular groove 98. Two such pins may be employed, if desired.

Thus the assembly 16 at the upper end of the tension members 74, 75 in Fig. 2 is adapted to exert a pressure on the end of the tilting lever 28 by means of the jack screw 85 and ratchet lever 89.

At their opposite ends the tension members 74, 75 are provided with a multiplicity of regularly spaced apertures 98, 99 preferably arranged in pairs for engagement with the pivot stirrup 100, which forms a part of the assembly 17 at the lower end of the tension members 74, 75.

The pivot stirrup 100 may comprise a cast metal member having a pair of parallel flanges 101 and 102 joined by an integral shaft 103 and held parallel to each other in position to engage the inside of the wooden tension members 74, 75.

The stirrup 100 acts as a spacer and is provided with laterally projecting cylindrical lugs 104 at each end of the shaft 103 for engaging in the apertures 99 of the tension members 74, 75. The parallel flanges or plates 101, 102 of the stirrup have apertures 105 adjacent their opposite ends to register with the apertures 98 in the tension members 74, 75.

In order to reinforce the wooden tension members 74, 75 against splitting, each one is covered at the assembly 17 by means of a metal plate 106, 107, which engages the outside of each tension member 74, 75 and has a pair of edge engaging flanges 108, 109. The edge engaging flanges hub the edges of the wooden tension members 74, 75 and prevent them from splitting.

The reinforcing plates 106, 107 are provided with apertures 110 for passing the cylindrical shanks of the eye bolt 111. The eye bolt 111 also passes through the apertures 98 in the tension members 74, 75 and extends into the bearing aperture 32 of the lower tilting lever 29.

The cylindrical shank 112 of the eye bolt 111 may extend through the plates 106, tension members 74, 75, tilting lever 29, and plate 107; and may be provided at its opposite end with threads at 113 for engagement with the threads of an eye nut 114. Thus the lower tilting lever 29 in Figs. 1 and 2 is pivotally mounted between the tension members 74, 75 at an adjusted position so that the length of the tension members 74, 75 is suitable for relieving the strain on an insulator string of a particular length.

The method and operation and use of the strain carrier is as follows: If the yoke is of the type comprising a flat plate, as indicated at 23, the tilting levers 28, 29 are used without the adapter 59. If the yoke is of the type shown in Fig. 1, the adapter 59 must be pivotally mounted on the bolt 58.

The strain carrier is first adjusted to a suitable length by having the pivot assembly 17 and the lower tilting lever 29 secured to the tension

members 14, 15 at the proper pair of apertures 98, 99.

The jack screw 85 is preferably retracted outward as much as possible in order to provide it with an operating range when the carrier is attached to the yokes. The two tilting levers are then mounted on the yokes, the yokes being received in the grooves between the slotted ends of the tilting levers; and the tilting levers are secured in place by inserting the eye bolts 47 in the apertures 45, the eye bolt passing through the triangular aperture 22 in Fig. 1 of the yoke 13, or the eye bolt passes below the lower edge 48 of the yoke 23, as shown in Fig. 3.

The base 42 of the slot 40 in each tilting lever 28 or 29 bears against the diagonal edge 43 of each yoke in Fig. 3 or it is the adapter which bears against this edge 64 in Fig. 1.

The open eye bolts 69 and 73 are then provided with elongated wooden rods, which serve as a cradle for the string of insulators, such as the string 11. The device is now ready to relieve the strain on this insulator; and this is done by means of the ratchet lever 89.

The ratchet lever 89 rotates shaft 85 in its threaded bore 84 in the block 78, causing the shaft to progress downwardly in Figs. 1 and 2 and exerting a pressure or a push on the stub shaft 94 carried by tilting lever 28. This effectively shortens the space between the tilting levers 28, 29, tension being placed upon the tension members 74, 75 to pull the free ends of the levers 28, 29 toward each other.

The other ends of the levers 28, 29 are in effect rigidly connected to the yokes 13, 14 (Fig. 1); and the two yokes are caused to pull toward each other on the side on which the strain carrier is applied. This shortens the space between the two points of attachment 15, 15 of the insulator string 11 and removes the strain from this insulator string, the strain being taken by the tension members 74, 75.

The insulator string may then be removed, repaired, and replaced; and the jack shaft 85 may be backed off to place the strain again on the insulator string. All of the parts of the strain carrier which have to be handled when it is applied to the line are insulated or provided with eye bolts, such as the eye bolts 47, so that they can be manipulated by means of an insulated clamp stick.

In the present device the jack is located outside of the torque levers, thus eliminating entirely metal parts between the torque levers and increasing the insulation. Increased insulation is of the utmost importance in a tool of this kind, as it reduces the possibility of leakage currents or surge flash-over, and thus increases the safety to the operator. The jack is also located in the present device more conveniently for the user.

The present strain carrier is usable with all types of yoke plates; and it is not necessary to have two sets of torque arms. The length of the strain carrier can be adjusted for any length of string insulator.

The wooden tension members are reinforced against spreading or splitting; and the torque arms are pivotally connected to the tension members to permit the pivotal movement which is necessary.

While I have illustrated a preferred embodiment of my invention, many modifications may be made without departing from the spirit of the invention; and I do not wish to be limited to the precise details of construction set forth, but desire

to avail myself of all changes within the scope of the appended claims.

Having thus described my invention, what I claim as new and desire to secure by Letters Patent of the United States, is:

1. In a strain carrier for relieving the strain of one of a pair of string insulators supported by yokes, the combination of a pair of insulating tension members, said tension members being secured in spaced relation and parallel to each other, with a pair of torque arms, both torque arms having free ends pivotally mounted between said tension members and both torque arms being provided at their opposite ends with means for fixed securing to the yokes which carry the string insulators, and force multiplying means mounted between said insulating tension members and exerting a push on one of said torque arms to tilt the yokes which support the string insulators and relieve the strain on one of said string insulators, the said force multiplying means being located outwardly of both torque arms so that the insulating tension members utilize the entire space between the torque arms for insulation.

2. In a strain carrier for relieving the strain of one of a pair of string insulators supported by yokes, the combination of a pair of insulating tension members, said tension members being secured in spaced relation and parallel to each other, with a pair of torque arms, both torque arms having free ends pivotally mounted between said tension members and both torque arms being provided at their opposite ends with means for fixed securing to the yokes which carry the string insulators, and force multiplying means mounted between said insulating tension members and exerting a push on one of said torque arms to tilt the yokes which support the string insulators and relieve the strain on one of said string insulators, the said force multiplying means being located outwardly of both torque arms so that the insulating tension members utilize the entire space between the torque arms for insulation, said force multiplying means comprising a screw shaft mounted in a threaded member fixedly secured between said insulating tension members, the end of said shaft urging one of said torque arms inwardly.

3. In a strain carrier for relieving the strain of one of a pair of string insulators supported by yokes, the combination of a pair of insulating tension members, said tension members being secured in spaced relation and parallel to each other, with a pair of torque arms, both torque arms having free ends pivotally mounted between said tension members and both torque arms being provided at their opposite ends with means for fixed securing to the yokes which carry the string insulators, and force multiplying means mounted between said insulating tension members and exerting a push on one of said torque arms to tilt the yokes which support the string insulators and relieve the strain on one of said string insulators, the said force multiplying means being located outwardly of both torque arms so that the insulating tension members utilize the entire space between the torque arms for insulation, said force multiplying means comprising a screw shaft mounted in a threaded member fixedly secured between said insulating tension members, the end of said shaft urging one of said torque arms inwardly, said shaft being rotatably mounted upon a sliding member guided between said insulating tension members and having a

socket for engaging a curved formation on the end of the adjacent torque arm.

4. In a strain carrier for relieving the strain of one of a pair of string insulators supported by yokes, the combination of a pair of insulating tension members, said tension members being secured in spaced relation and parallel to each other, with a pair of torque arms, both torque arms having free ends pivotally mounted between said tension members and both torque arms being provided at their opposite ends with means for fixed securing to the yokes which carry the string insulators, and force multiplying means mounted between said insulating tension members and exerting a push on one of said torque arms to tilt the yokes which support the string insulators and relieve the strain on one of said string insulators, the said force multiplying means being located outwardly of both torque arms so that the insulating tension members utilize the entire space between the torque arms for insulation, the said torque arms being formed at said opposite ends with a pair of lateral flanges separated by a slot, the said slot fitting over and having its base engaging the diagonal edge of the adjacent yoke, and means carried by the said flanges for engaging the opposing surface on said yoke to fixedly secure each torque arm to its yoke.

5. In a strain carrier for relieving the strain of one of a pair of string insulators supported by yokes, the combination of a pair of insulating tension members, said tension members being secured in spaced relation and parallel to each other, with a pair of torque arms, both torque arms having free ends pivotally mounted between said tension members and both torque arms being provided at their opposite ends with means for fixed securing to the yokes which carry the string insulators, and force multiplying means mounted between said insulating tension members and exerting a push on one of said torque arms to tilt the yokes which support the string insulators and relieve the strain on one of said string insulators, the said force multiplying means being located outwardly of both torque arms so that the insulating tension members utilize the entire space between the torque arms for insulation, the said torque arms being formed at said opposite ends with a pair of lateral flanges separated by a slot, the said slot fitting over and having its base engaging the diagonal edge of the adjacent yoke, and means carried by the said flanges for engaging the opposing surface on said yoke to fixedly secure each torque arm to its yoke, said latter means comprising an eye bolt passing through both flanges and engaging the inner side of the yoke.

6. In a strain carrier for relieving the strain of one of a pair of string insulators supported by yokes, the combination of a pair of insulating tension members, said tension members being secured in spaced relation and parallel to each other, with a pair of torque arms, both torque arms having free ends pivotally mounted between said tension members and both torque arms being provided at their opposite ends with means for fixed securing to the yokes which carry the string insulators, and force multiplying means mounted between said insulating tension members and exerting a push on one of said torque arms to tilt the yokes which support the string insulators and relieve the strain on one of said string insulators, the said force multiplying means being located outwardly of both torque arms so that the insulating tension members

utilize the entire space between the torque arms for insulation, the said torque arms being formed at said opposite ends with a pair of lateral flanges separated by a slot, the said slot fitting over and having its base engaging the diagonal edge of the adjacent yoke, and means carried by the said flanges for engaging the opposing surface on said yoke to fixedly secure each torque arm to its yoke, said latter means comprising an eye bolt extending through both flanges and through an aperture in the yoke and engaging the side of said aperture at surfaces which oppose the base of said slot, and which oppose the movement of the torque arm off the yoke.

7. In a strain carrier for dead end strain insulators, a torque arm comprising a cast metal member formed at one of its ends with a transverse cylindrical formation having an axial aperture serving as a bearing, the said torque arm tapering toward said end and having a laterally turned enlargement at the other end, said laterally turned enlargement being provided with a slot separating the enlargement into two parallel flanges, the slot being large enough to receive the edge of a yoke, and the extreme end of said laterally turned enlargement having its flanges provided with registering apertures, and an eye bolt having its shank in said apertures for engaging an opposing surface of a yoke when the base of a slot between said flanges engages the diagonal edge of said yoke.

8. In a strain carrier for dead end strain insulators, a pair of parallel insulating tension members, a torque arm comprising a cast metal member formed at one of its ends with a transverse cylindrical formation having an axial aperture serving as a bearing, the said torque arm tapering toward said end and having a laterally turned enlargement at the other end, said laterally turned enlargement being provided with a slot separating the enlargement into two parallel flanges, the slot being large enough to receive the edge of a yoke, and the extreme end of said laterally turned enlargement having its flanges provided with registering apertures, and an eye bolt having its shank in said apertures for engaging an opposing surface of a yoke when the base of a slot between said flanges engages the diagonal edge of said yoke, and a pivotal connection for said torque arm to said pair of insulating tension members comprising an eye bolt passing through both tension members and through said bearing aperture, and provided with an eye nut on its end.

9. In a strain carrier for dead end strain insulators, a pair of parallel insulating tension members, a torque arm comprising a cast metal member formed at one of its ends with a transverse cylindrical formation having an axial aperture serving as a bearing, the said torque arm tapering toward said end and having a laterally turned enlargement at the other end, said laterally turned enlargement being provided with a slot separating the enlargement into two parallel flanges, the slot being large enough to receive the edge of a yoke, and the extreme end of said laterally turned enlargement having its flanges provided with registering apertures, and an eye bolt having its shank in said apertures for engaging an opposing surface of a yoke when the base of a slot between said flanges engages the diagonal edge of said yoke, and a pivotal connection for said torque arm to said pair of insulating tension members comprising an eye bolt passing through both tension members and

through said bearing aperture, and provided with an eye nut on its end, and means for holding said insulating tension members in parallel spaced relation, comprising a U-shaped stirrup having apertures for said eye bolt and having its legs between said insulating members.

10. In a strain carrier for dead end strain insulators, a pair of parallel insulating tension members, a torque arm comprising a cast metal member formed at one of its ends with a transverse cylindrical formation having an axial aperture serving as a bearing, the said torque arm tapering toward said end and having a laterally turned enlargement at the other end, said laterally turned enlargement being provided with a slot separating the enlargement into two parallel flanges, the slot being large enough to receive the edge of a yoke, and the extreme end of said laterally turned enlargement having its flanges provided with registering apertures, and an eye bolt having its shank in said apertures for engaging an opposing surface of a yoke when the base of a slot between said flanges engages the diagonal edge of said yoke, and a pivotal connection for said torque arm to said pair of insulating tension members comprising an eye bolt passing through both tension members and through said bearing aperture, and provided with an eye nut on its end, and means for holding said insulating tension members in parallel spaced relation, comprising a U-shaped stirrup having apertures for said eye bolt and having its legs between said insulating members, said stirrup having extensions at its yoke extended into apertures in each of said insulating tension members.

11. In a strain carrier for dead end strain insulators, a pair of parallel insulating tension members, a torque arm comprising a cast metal member formed at one of its ends with a transverse cylindrical formation having an axial aperture serving as a bearing, the said torque arm tapering toward said end and having a laterally turned enlargement at the other end, said laterally turned enlargement being provided with a slot separating the enlargement into two parallel flanges, the slot being large enough to receive the edge of a yoke, and the extreme end of said laterally turned enlargement having its flanges provided with registering apertures, and an eye bolt having its shank in said apertures for engaging an opposing surface of a yoke when the base of a slot between said flanges engages the diagonal edge of said yoke, and a pivotal connection for said torque arm to said pair of insulating tension members comprising an eye bolt passing through both tension members and through said bearing aperture, and provided with an eye nut on its end, each of said insulating tension members being re-enforced by an exterior plate having an aperture for said eye bolt, and each plate having transverse flanges engaging the edges of said insulating tension members.

12. In a strain carrier for a string insulator carried by a pair of yokes, a pair of torque arms, each torque arm having at one end means for fixed securement to one of said yokes, and each torque arm being provided at its other end with a bearing bore, a pair of elongated insulating tension members and means for securing said insulating members in spaced relation to each other, means for pivotally attaching the bearing of one torque arm between said insulating members, and means for exerting a force on the bearing end of the other torque

arm when located between said insulating members at the opposite end of said insulating members, said latter means comprising a jack screw threadedly mounted between said insulating members outwardly of said latter torque arm, and having means for engagement with said bearing end, and said latter means comprising, a slider having spaced flanges for sliding engagement with said insulating members and having a trough for engagement with a suitable shaft in said bearing end.

13. In a strain carrier for dead end strain insulators, a torque arm comprising a cast metal member formed at one of its ends with a transverse cylindrical formation having an axial aperture serving as a bearing, the said torque arm tapering toward said end and having a laterally turned enlargement at the other end, said laterally turned enlargement being provided with a slot separating the enlargement into two parallel flanges, the slot being large enough to receive the edge of a yoke, and the extreme end of said laterally turned enlargement having its flanges provided with registering apertures, and an eye bolt having its shank in said apertures for engaging an opposing surface of a yoke when the base of a slot between said flanges engages the diagonal edge of said yoke, the said torque arm being provided with a pair of spaced, depending, open eye members carrying a pair of elongated rods serving as a cradle for the strain insulator.

14. In a prying torque lever for relieving the strain on one of a pair of string insulators, while transferring the load to the other string insulator, said string insulators being mounted on a yoke, comprising an elongated lever having a bearing surface on its lower side for engaging a part carried by the yoke, adjacent the end of the yoke and adjacent the end of the loaded string insulator, said lever having a pair of flanges separated by a longitudinally extending slot for receiving said yoke, and said flanges carrying a prying bolt passing through two registering apertures in the flanges, said bolt exerting a prying force on a part of the yoke which is spaced from said loaded string insulator, said bolt passing through an aperture in the yoke and engaging the side of said aperture, and said flanges carrying a pivotally mounted adapter which is swingable into engagement with the top of the yoke above the lowered string insulator, for exerting a prying action through the intermediary of said adapter.

15. An elongated insulated tension assembly comprising a pair of elongated rectangular wooden strips, the said wooden strips being secured together by transverse threaded members

adjacent each of their ends in parallel relation to each other, a cross head carried by one of said transverse threaded members, and having a threaded member in said cross head, a screw jack having a threaded bolt mounted in said latter threaded member, and a slider acted on by said latter threaded bolt by pushing action to cause an effective shortening of the space between the slider and the other end of the tension assembly, to place a tension on said wooden members.

16. An elongated insulated tension assembly comprising a pair of elongated rectangular wooden strips, the said wooden strips being secured together by transverse threaded members adjacent each of their ends in parallel relation to each other, a cross head carried by one of said transverse threaded members, and having a threaded member in said cross head, a screw jack having a threaded bolt mounted in said latter threaded member, and a slider acted on by said latter threaded bolt by pushing action to cause an effective shortening of the space between the slider and the other end of the tension assembly, to place a tension on said wooden members, said wooden members being provided with a multiplicity of apertures adjacent said other end.

17. In a tension insulating member, the combination of a pair of elongated wooden insulating strips of rectangular cross section with means for pivotally mounting a torque arm on one of said strips, and a second torque arm pivotally carried by the other end of said strips, said second torque arm being carried by a transverse eye bolt, each of said strips being provided with pairs of registering apertures, and the eye bolt passing through one set of registering apertures, and a spacer member between said strips, said spacer member having a spacing yoke and a pair of engaging flanges, said flanges having lugs for engaging in the other registering apertures, and said flanges having apertures for passing said eye bolt.

DAVID CHARLES HUBBARD.
